UNITED STATES PATENT OFFICE.

GIOVANNI BOGNI, OF SESTO CALENDE, ITALY.

MORSE TELEGRAPHIC APPARATUS.

932,105.

Specification of Letters Patent.

Patented Aug. 24, 1909.

Application filed August 28, 1905. Serial No. 276,157.

To all whom it may concern:

Be it known that I, GIOVANNI BOGNI, a subject of the King of Italy, residing at 39 Via Venti Setembre, Sesto Calende, Lombardy, Italy, have invented certain new and useful Improvements in Morse Telegraphic Apparatus; and I do hereby declare the following to be a full, clear, and exact description of the invention, such as will enable others skilled in the art to which it appertains to make and use the same.

The object of my invention is to provide apparatus whereby the two elementary signs of the Morse alphabet (dash and dot) may be replaced by a combination of dashes and dots, which in their most simple form allow of five different elementary signs being used, namely:

20   i   2   3   4   5

While the use of said five elementary signs allows of the ordinary telegraphic correspondence being carried out in a substantially much simpler and quicker manner than it is possible by means of only two elementary signs, the new elementary signs are evidently capable of forming a very wide number of combinations, which admit of a telegraphic code being drawn up that is itself simpler and more efficient than those based on the ordinary Morse alphabet.

In the accompanying drawings, which are given by way of example only, Figures 1 and 2 represent a Morse transmitter and Figs. 3 and 4 a Morse receiver as modified in order to adapt them for the use of my improved alphabet. They differ from the apparatus as now in use in as far as the transmitter is provided with a second key t_2 (Figs. 1 and 2).

In said figures a shows the line, b the battery, c the earth, t_1 t_2 the transmitter keys; l the paper ribbon, m_1 , m_2 the electromagnets of the receiver. On depressing key t_1 (Fig. 1) only a part of the battery b is actuated, the current generated is only sufficient to draw down the armature s_1 of the electromagnet M_1 and the usual dashes and dots are obtained. If on the contrary the key t_2 be depressed, the whole battery b is put in action and the current energizes electromagnet M_2 besides electromagnet M_1 and therefore draws down not only armature s_1 but also armature s_2 . In this case the double signs : == are obtained. The armature

s_2 (Fig. 4) is provided with a side projection A, which causes the armature s_1 to partake of the movement of the electromagnet s_2 when the same is caused to swing in the direction of the arrow. The sign is obtained by depressing the key t_1 for a longer time and contemporaneously exerting a momentary action only on the key t_2 . It will easily be understood how such other signs such as two dots above a dash, one dot above another dot, or a tremulous vibration of both keys might be recorded.

Morse's apparatus modified as above described is, as already told, available for using the ordinary Morse's alphabet if desired, and so Morse's apparatus modified according to my invention may be used in connection with ordinary Morse apparatus.

Having now described my invention and how the same is to be carried out, what I desire to protect by Letters Patent is:

1. In a telegraphic apparatus, the combination with the receiving armatures and electro-magnets for operating the same; of a battery composed of sections; a plurality of transmitting keys separately connected with different sections of said battery whereby a larger or smaller number of the elements of said battery may be introduced into the telegraphic circuit to energize different electro-magnets; and means interacting between the receiving armatures whereby the armature actuated by a key which introduces more than one of the sections of said battery, will impart movement to its adjacent armature operable by a less number of sections of said battery.

2. In a telegraphic apparatus, the combination with a pair of receiving armatures adjacently arranged, electro-magnets for operating the same and a battery of elements, one of said electro-magnets being made effective by a portion of said battery while the other electro-magnet requires the entire battery to make it effective; of a pair of transmitting keys adjacently arranged, one of said keys being connected up to introduce only that portion of the battery which energizes the first magnet, and the other key being connected up to introduce the entire battery to energize the second magnet; and means connected with the receiving armature which is actuated only by the entire battery, whereby the motion of said armature is transmitted to the armature which is actuated by a portion only of the battery.

3. In a telegraphic apparatus, the combination of a plurality of transmitting keys, a plurality of electro-magnetically operated receiving armatures, means for operating each one of the receiving armatures by depressing one of the transmitting keys and means for transmitting the movement from one receiving armature to another.

4. In a telegraphic apparatus, the combination of two transmitting keys a battery, means by which only a portion of said battery is thrown into action by the depression of one of said keys, means whereby the entire battery is thrown into action by the depre-

sion of the other of said keys, two electro-magnets which are respectively energized by the depression of said transmitting keys, two recording armatures each of which are actuated by one of said electro-magnets, and a lug upon one recording armature in virtue of which the movement thereof is transmitted to the other recording armature.

In testimony whereof I affix my signature in presence of two witnesses.

GIOVANNI BOGNI.
